UNITED STATES PATENT OFFICE.

GEORGE PLUMMER HOWE, OF BOSTON, MASSACHUSETTS.

MAGAZINE FOR RAPID-FIRE ARMS.

1,119,756.

Specification of Letters Patent.

Patented Dec. 1, 1914.

Application filed February 11, 1914. Serial No. 818,126.

To all whom it may concern:

Be it known that I, GEORGE PLUMMER HOWE, a citizen of the United States, and resident of Boston, in the county of Suffolk 5 and State of Massachusetts, have invented new and useful Improvements in Magazines for Rapid-Fire Arms, of which the following is a specification.

My invention relates to the construction 10 and operation of rapid fire arms and is adaptable either to the full automatic or the semi-automatic types of such arms.

The object of my invention is to provide 15 means for re-loading the magazines of fire- arms of the general type designated, with certainty and rapidity.

For the purposes of illustrating my invention and improvements, I take as an example of the type of firearm above designated, 20 the well known Colt automatic pistol. In this firearm the cartridges which constitute the ammunition are arranged side by side in a nearly vertical column in the magazine, the line of feed from the magazine being 25 transverse to the axes of the individual cartridges and the magazine being located in the handle or grip of the pistol.

In the drawings hereto annexed which 30 illustrate my inventions and improvements,—Figure 1 is a side elevation of part of a Colt automatic pistol comprising my improvements, the magazine being shown as closed; Fig. 2 is a similar view showing the magazine open; Fig. 3 is a cross section 35 taken at the line 3—3 of Fig. 2; Fig. 4 shows a plurality of cartridges held as a unit in the ammunition clip which is a feature of my improvements; Fig. 5 is a vertical section taken through the magazine showing

40 the magazine only partly filled with cartridges, which are disengaged from the ammunition clip; Fig. 6 is a section taken along the line 6—6 of Fig. 5, showing the ammunition clip in rear elevation; Fig. 7 is 45 a section through the magazine cover taken on the line 7—7 of Fig. 1; Fig. 8 is a section of the magazine clip taken on the line 8—8 of Fig. 10 looking against the arrow points; Fig. 9 is a rear elevation of the 50 ammunition clip with the members thereof interlocked and in cartridge holding position; Fig. 10 is an elevation of the cartridges and the ammunition clip, the latter being shown with its members expanded and 55 disengaged from the cartridges; Fig. 11 is a broken sectional view of portions of the

Colt automatic pistol showing a modified or alternative form in which my inventions and improvements may be embodied; Fig. 12 is a section taken on the line 12—12 of 60 Fig. 11 and showing the magazine case nearly but not quite inserted into the chamber therefor; Fig. 13 is a side elevation, partly broken away, of the magazine case; Fig. 14 is a front view of the ammunition 65 clip with its members in cartridge embracing position; Fig. 15 is a similar view of the ammunition clip with its members in cartridge releasing position; Fig. 16 shows the cartridges assembled in the clip; Fig. 17 70 is a cross section of the clip shown in Fig. 14 with a cartridge exhibited in elevation; Fig. 18 is another cross section of the ammunition clip, this section being taken through one of the cam slots therein; Fig. 19 is a 75 side view, partly in broken section, of a portion of a Colt automatic pistol comprising another alternative form of my inventions and improvements; Fig. 20 is a vertical section through the magazine case shown in 80 Fig. 19; Fig. 21 is a rear elevation of the same magazine case; Fig. 22 is a cross section of the same magazine case taken at the line 22—22 of Fig. 19; Fig. 23 shows a plurality of cartridges held by an ammunition 85 clip of peculiar construction; Fig. 24 is a plan view of a portion of said ammunition clip; and Fig. 25 shows a magazine case in cross section and the ammunition clip and cartridges in end view, the latter in the act 90 of insertion into the magazine case.

Referring to Figs. 1 to 10, inclusive, which illustrate that form of my inventions and improvements which I regard as preferable, the grip G constitutes the magazine (no 95 separable magazine case such as is involved in the structures illustrated in Figs. 11 to 25, inclusive, being included in this preferred form of my improvements). The magazine consisting thus of the grip G which is suitably chambered for the purpose, is provided with a lateral opening at G² which opening is substantially as large in longitudinal dimension (i. e. along the line of feed of the magazine) as the ammunition space of the 100 magazine. This lateral opening in the magazine is covered by a slidably cover C of which the plate S is slidably fitted into the magazine opening G². The plate S is channeled obliquely to receive the latch L (Figs. 105 1, 2 and 7) which when the cover C is closed engages with a notch N and when the cover

is open, with the notch N', both these notches being formed in a side of the magazine opening G². The latch L is impelled toward notch-engaging position by the spring L² and may be withdrawn from notch-engaging position by means of the knurled boss L' which, projecting into a recess C' in the cover C, may conveniently be operated by the thumb or finger.

10 In the ammunition chamber of the magazine there is provided the usual ammunition feeding spring D with its follower F. The follower F (see Fig. 5) is provided with a side plate F² from which a spur F' is laterally and outwardly bent so as to engage with the projection S' on the inside of the plate S. When, therefore, the cover C (the latch L being first withdrawn for the purpose) is slid downward from the position shown in 15 Fig. 1 to that shown in Fig. 2, the projection S' engages the spur F' and compresses the spring D, opening the magazine and preparing the space above the follower F for the insertion of ammunition.

20 While it would be possible to insert loose cartridges into the magazine through the lateral opening provided by withdrawal of the cover C, I consider it preferable to prepare the ammunition so that several cartridges—usually a full magazine charge—may be inserted as a unit into the magazine through the lateral opening. For this purpose I have contrived an ammunition clip which serves to hold a plurality of cartridges assembled as a unit and ready for insertion into the magazine and which also co-operates with the magazine mechanism and becomes a functional factor related to the magazine mechanism after the clip and the 25 cartridges embraced thereby have been introduced into the magazine.

25 A simple and I believe the best form of ammunition clip is shown in Figs. 3, 4, 5, 6, 8, 9 and 10. Referring to Fig. 9, which shows the ammunition clip on a large scale, the clip comprises two members, namely, the plates A' and A². These plates are each turned up at an edge to form the cartridge-engaging lips A³, A⁴, respectively. The plate 30 A' has inclined cam slots A⁵ cut in it and the plate A² is provided with spurs A⁶ which extend through the cam slots A⁵ and are bent around the plate A' so that the two plates A' and A² are secured together. In assembling the cartridges B in the clip, the two plates are slid longitudinally on each other to the position shown in Fig. 10. In this position the co-operation of the cam slots A⁵ and spurs A⁶ cause the two plate members A' and A² to spread apart so that the cartridges 35 B can be inserted between the flanges or lips A³ and A⁴ of the plates A' and A². The plates A' and A² are then slid back into the relation shown in Fig. 9; this movement 40 drawing the lips A³ and A⁴ into engagement

with the usual channels at the bases of the cartridge shells. Then the corners A' and A² of the plates A' and A², respectively, are slightly bent up so as to prevent the cartridges B from slipping out lengthwise. It 45 will be observed that there is a shoulder A¹⁰ upon plate A' and a similar shoulder A⁹ upon plate A², these for a purpose presently to be described.

50 The magazine being opened (Fig. 2) a clip filled with cartridges as above described is inserted as a unit into the lateral openings G² of the magazine and thereupon the latch L is withdrawn from engagement with notch N' and the slidable cover C moved upward to close the opening G². This movement of the cover C releases the hold of projection S' upon the spur F', the latter being on the follower F so that the spring D' exerts pressure upon the lowermost cartridge in the magazine. This pressure applied at first upon the forward end of the cartridge tends to tilt the lowermost cartridge and the others in turn toward the 55 position shown in Fig. 5, but until the cartridges are released from the embrace of the ammunition clip, this tilting movement cannot be completed.

55 To release the cartridge from the embrace of the ammunition clip, the two plate members A' and A² must be slid lengthwise on one another so that the cam slots A⁵ co-operating with the spurs A⁶ will compel the two plates A' and A² to spread apart and thus to disengage the cartridges from the 60 lips A³ and A⁴. At one side of the magazine in the upper part thereof (see Fig. 6) there is provided a shoulder G' and on the slide S there is provided the projection S². As the closing movement of the cover C is 65 being completed the projection S² engages with the shoulder A¹⁰ upon plate A² while the similar shoulder A⁹ upon plate A' strikes against the shoulder or abutment G'. Then the final closing movement of the cover C 70 obliges the plate A² to slide upward to the position shown in Fig. 6 while plate A' is restrained by the abutment G'; the two plates A' and A² are thus slid longitudinally 75 relatively to one another and are at the same time spread apart through the co-operation of the cam slots A⁵ and the spurs A⁶. The cartridges are thereby released from the embrace of the ammunition clip which thereafter 80 plays no part in the operation of the 85 firearm.

85 When the magazine has been emptied of cartridges, and it is desired to insert a fresh charge, the cover C is again opened. This releases the ammunition clip which readily falls out or may be shaken out to make place for a fresh clip with the cartridges assembled in it.

90 Figs. 11 to 18, inclusive, illustrate an alternative form in which my improvements 95

may be embodied, and one in which the inner sheet metal magazine case to be found in the Colt automatic pistol as at present manufactured, is retained. This form of my invention, therefore, is adapted to incorporation into the structure of automatic pistols as now manufactured and may possess special practical value for that reason, although as I have already intimated I regard the structure illustrated in Figs. 1 to 10 inclusive as a better concrete example of my improvements. Referring to Fig. 11, M represents the sheet metal magazine case which is housed within the pistol grip G. This magazine case is provided with notches at M' and M², which engage with the toe H' of the spring catch H. The magazine case M is also slotted at M³, this slot providing a way for the movement of the spur F', formed at the lower edge of the side wall F² on the follower F and projecting outward through the slot M³. At the bottom of the slot M³ there is a lateral notch M⁴ to engage the spur F' when the follower F is drawn down to compress the magazine spring D. One side, to wit, the rear, of the magazine case M is cut away, forming a lateral opening at the rear of the magazine case which is substantially of the same longitudinal dimensions as the ammunition space of the magazine. The metal wall near the base of the case M is notched or stepped as seen in Fig. 12, and the metal at one side is turned in to form a stiff shoulder at M⁶ (Fig. 13). At the upper end of the case the lateral opening is bounded by a strip of metal M⁵, which constitutes a bridge from one side to the other of the magazine case M.

To prepare the magazine case M for reloading, the spring catch H is sprung outward, disengaging the toe H' from the notch M², and the magazine is then slid down out of the grip G in the usual way, the spring clip H moving inward when the notch M' arrives at a position opposite the toe H'. The magazine case M is then swung forward on the toe H' as a pivot, as shown in dotted lines in Fig. 11, to expose the lateral opening at the rear thereof to its full extent. The ammunition unit consisting of a group of cartridges B is held in a clip of practically the same construction as the clip already described in connection with Figs. 1 to 10, inclusive, so that a further description of all the details of this ammunition clip is unnecessary.

When the magazine case M is protruded to the position shown in dotted lines in Fig. 11, the follower F is moved downward by means of the spur F' and the spur F' inserted in the notch M⁴, so that the spring D is held compressed between the follower and the base plate of the magazine case M. Then when the ammunition unit consisting

of cartridges B held in the ammunition clip 65 is inserted as a unit in the magazine case M through the rear opening thereof, the lowermost cartridge in the clip bears on the follower F and tips it downward and forward, releasing the spur F' from the notch M⁴. 70 Then the magazine case M is turned rearwardly and reinserted into the chamber in the grip G. At the close of this movement of reinsertion of the magazine case M, the stud E (Figs. 11 and 12) which projects into 75 the space within the pistol grip and is carried on the end of the spring E', stands in the path of the shoulder A¹⁰ on the clip plate A' and arrests the plate A' while the ledge M⁶ (Fig. 13) bearing on the corner A⁹ of 80 plate A², continues to force plate A² upward. By this means the plates A' and A² are slid with relation to each other and spread apart by the intersection of the cam-slots A⁵ and spurs A⁶, releasing the cartridges from the embrace of the lips A³ and A⁴. In the discharge of the firearm the cartridges are fed upward in the usual manner. When the magazine is emptied the magazine case M is again extruded from the 90 clip G and the ammunition clip remaining therein either falls out or may be easily removed to make way for the insertion of a new ammunition unit.

The upper side of the stud E is beveled, 95 and the top edge of the magazine case M is inclined at M⁸ (Fig. 12) so that the stud E yields to allow the magazine case M to pass it in either direction.

In the examples of my improvements 100 hereinabove described the ammunition clip enters the magazine, remains there, and co-operates functionally with the magazine mechanism to release the cartridges, and may be discarded after the magazine has 105 been discharged.

In the form of my invention shown in 110 Figs. 19 to 25, inclusive, the ammunition clip co-operates with the magazine case to deliver the cartridges to the case and is thereupon withdrawn before reinsertion of the magazine case into the grip G, leaving the cartridges engaged with the magazine case without the clip. Referring to Figs. 19 to

25, it will be seen that the arm is of the same general character as that illustrated in Figs. 11 to 18 inclusive, in that the magazine involves the use of a sheet metal case M, which in so far as concerns its mode of extrusion and replacement in the magazine space 115 within the grip G, is constructed in much the same manner as the magazine case shown in Fig. 11, and therefore need not be described in full detail. In this instance, however, the opening at the rear of the case M is formed so that the sides of the magazine case are inturned so as to form cartridge gripping lips M⁶ and M⁷, and notches

120

125

4

M⁸ and M⁹ are formed in the side of the case at the ends of the lip M⁶ so that the latter is given a proper degree of spring action in order to function in the reception and retention of the cartridges. The ammunition clip shown generally in Fig. 23 and designated by the letter J, consists of a piece of sheet metal bent up into channel form with an internal ridge J⁴ and spring plates J' secured to the sides of the channel by means of end pieces J² which are bent around the end of the channel piece. These spring plates curve inwardly so as to embrace and hold the cartridges B, the inner edges of the spring plates J' entering the annular grooves B' near the bases of the cartridges. In loading the clips the cartridges are preferably inserted at one end and slid along in the clip, and when the clip is full the ends of the spring plates J' are bent in as at J³ to retain the row of cartridges in place.

When the magazine case M is retracted and the follower F pressed down and caught with its spur F' in the notch M⁴ as shown in the dotted lines of Fig. 19, the charge 25 of cartridges held in the ammunition clip is inserted through the opening at the rear of the magazine case M. As will be seen in Fig. 25, which represents the cartridges entering the magazine case, the clip slips over the outside of the magazine case, the sides of the magazine case engaging the inturned portions of the spring plates J' and springing them outwardly to disengage them from the grooves B' in the cartridges. Further movement of the clip J forces the cartridges B into the case M, the ridge J⁴ pressing against the bases of the cartridges for this 30 purpose. Finally the lip M' springs into the grooves B' in the cartridge B, the lip M⁸ pressing against the opposite side of the cartridges and holding them firmly in place. The entrance of the cartridges into the magazine case causes the lowermost cartridge to press upon the follower F, tilting it downward and forward, thus releasing the spur F' from the notch M² so that the follower bears upon the row of cartridges under stress of the spring D. As in the Colt 35 automatic pistol at present manufactured, the inturned lips M⁸ (Fig. 21) at the top of the magazine case M, hold the cartridges against movement until the cartridge feeding mechanism (not here shown) thrusts the topmost cartridge forward and upward, sliding it out from under the lips M⁸.

It will now be observed that the several examples of my improvements hereinabove 60 described have this characteristic in common: That the ammunition magazine is provided with a lateral opening of substantially the same longitudinal dimensions as the ammunition space of the magazine, and that this lateral opening may be exposed or un-

covered so that a charge of ammunition (which may consist of more or less cartridges, as predetermined) can be inserted with a single movement. All these examples are also characterized by lateral loading of 70 the magazine with a plurality of cartridges inserted simultaneously or as a unit in a direction which is transverse to the line of feed of the ammunition during the operation of successive feed and discharge of the cartridges. 75

In those examples of my invention illustrated in Figs. 1 to 18, inclusive, a common characteristic also is: That the unit ammunition charges comprise the use of a clip 80 which normally engages a plurality of cartridges so that the clip and cartridges are manipulable as a single piece, and that this clip enters into the magazine and there co-operates with the magazine mechanism 85 to release the cartridges so that they may be operated on by the magazine feed in the usual manner.

In the preferred form of my invention illustrated in Figs. 1 to 10, inclusive, the 90 inner magazine case or shell is dispensed with and the grip of the arm alone suffices for the magazine member of the arm, and further, in this form by the act of exposing the interior of the magazine by moving the 95 cover which closes the lateral opening in the side of the magazine, the ammunition feeding spring and follower are operated to prepare the interior of the magazine for the reception of a fresh charge. 100

While the full expression of my improvements involves a structure which permits the insertion, as a unit, of a full magazine charge into the magazine in a direction transverse to the line of ammunition feed 105 during operation of the firearm, sundry characteristic features of these improvements may be employed with a measurable degree of convenience and advantage though less than the fullest measure. For example, 110 the combination of a movable magazine cover with the magazine spring follower, whereby opening of the lateral aperture in the magazine is accompanied by compression of the magazine spring, will enable cartridges to be fed into the magazine from the side, more readily and conveniently than they can be inserted into the present form 115 of magazine case as used in the Colt automatic pistol, since that magazine case is 120 withdrawn from its recess in the pistol grip and held loose in the hand while the cartridges are inserted successively. With a movable cover attached to the pistol grip, and connection between the cover and the 125 follower (an example of which is illustrated in Figs. 1 and 2), the magazine may be opened laterally and the follower depressed, making way for cartridges to be inserted one by one and successively, through an ap- 130

ture smaller in longitudinal dimension than the entire ammunition space in the magazine. In degree, the modes of operation and the convenience in loading will differ in such case from the mode of operation and attendant conveniences peculiar to the arrangement specifically shown in the drawings, Figs. 1 to 10, inclusive; but in kind, the mode and convenience of operation is the same in both these instances.

10. I claim:

1. In a firearm of the type designated, the combination of a magazine provided with a lateral opening of substantially the same longitudinal dimension as the ammunition space of the magazine, means to expose said lateral opening for the introduction of ammunition, a clip to hold a plurality of cartridges, whereby a plurality of cartridges is introduced as a unit, said clip comprising a pair of interlocked members, and means operated by the closure of the magazine to disengage the cartridges from the said clip members.

25. 2. In a firearm of the type designated, the combination of a magazine provided with a lateral opening of substantially the same longitudinal dimension as the ammunition space of the magazine, means to expose said lateral opening for the introduction of ammunition, a clip to hold a plurality of cartridges, whereby a plurality of cartridges is introduced as a unit, said clip comprising a pair of cartridge-embracing plates, one provided with inclined cam slots, the other with spurs engaging said cam slots, and means operated by the closure of the magazine to slide the said plates on each other and spread them, thereby to release the cartridges from the embrace of said plates.

30. 3. In a firearm of the type designated, the combination of a magazine provided with a lateral opening, a movable cover for said opening, an ammunition feeding spring in the magazine, and means actuated by the movable cover to compress the spring as the cover is moved to expose the said magazine opening.

4. In a firearm of the type designated, the combination of a magazine provided with a lateral opening of substantially the same longitudinal dimension as the ammunition space of the magazine, a slidably mounted cover for said opening, an ammunition feeding spring in the magazine, and means actuated by the sliding cover to engage and compress the spring as the cover is moved to expose the said magazine opening.

5. In a firearm of the type designated, the combination of a magazine provided with a lateral opening of substantially the same longitudinal dimension as the ammunition space of the magazine, a movable cover for said opening, a clip to hold a plurality of cartridges for simultaneous introduction of

said cartridges as a unit into the opening in the magazine, said clip comprising a pair of interlocked members, and means actuated by the magazine cover to disengage the cartridges from said clip members on closure of the cover.

6. In a firearm of the type designated, the combination of a magazine provided with a lateral opening of substantially the same longitudinal dimension as the ammunition

space of the magazine, a movable cover for said opening, a clip to hold a plurality of cartridges for simultaneous introduction of said cartridges as a unit into the opening in the magazine, said clip comprising a pair of cartridge-embracing plates, one provided with inclined cam slots, the other with spurs engaging said cam slots, and means, actuated by the magazine cover to engage and slide the said plates on each other and spread them, thereby to release the cartridges from the embrace of said plates.

7. In a firearm of the type designated, the combination of a magazine with a lateral opening of substantially the same longitudinal dimension as the ammunition space of the magazine, a slidably mounted cover for said opening, an ammunition feeding spring in the magazine, means carried by the sliding cover to engage and compress the spring as the cover is moved to expose the said magazine opening, and a clip to hold a plurality of cartridges, said clip and cartridges introduceable as a unit into the said magazine opening.

8. In a firearm of the type designated, the combination of a magazine provided with a lateral opening of substantially the same longitudinal dimension as the ammunition space of the magazine, a slidably mounted cover for said opening, an ammunition feeding spring in the magazine, means carried by the sliding cover to engage and compress the spring as the cover is moved to expose the said magazine opening,

105. 110. 115. 120. 125. 130. a clip to hold a plurality of cartridges, said clip and cartridges introduceable as a unit into the said magazine opening, the clip comprising a pair of interlocked members, and means actuated by the magazine cover to disengage the cartridges from said clip members on closure of the cover.

9. In a firearm of the type designated, the combination of a magazine provided with a lateral opening of substantially the same longitudinal dimension as the ammunition space of the magazine, a slidably mounted cover for said opening, an ammunition feeding spring in the magazine, means carried by the sliding cover to engage and compress the spring as the cover is moved to expose the said magazine opening, a clip to hold a plurality of cartridges for simultaneous introduction of said cartridges as a unit into the opening in the magazine, said clip com-

prising a pair of cartridge-embracing plates, one provided with inclined cam slots, the other with spurs engaging said cam slots, and means actuated by the magazine cover to engage and slide the said plates on each other and spread them on closure of the cover, thereby to release the cartridges from the embrace of said plates.

10. In a firearm of the type designated, the combination of a magazine provided with a lateral opening of substantially the same longitudinal dimension as the ammunition space of the magazine, a slidably mounted cover for said opening, an ammunition feeding spring in the magazine, means carried by the sliding cover to engage and compress the spring as the cover is moved to expose the said magazine opening, a clip to hold a plurality of cartridges, said clip and cartridges introduceable as a unit into said magazine opening, and a catch carried by said magazine cover to hold the same in place.

25. In a firearm of the type designated, the combination of a magazine provided with a lateral opening of substantially the same longitudinal dimension as the ammunition space of the magazine, a slidably mounted cover for said opening, an ammunition feeding spring in the magazine, means carried by the sliding cover to engage and compress the spring as the cover is moved to expose the said magazine opening, a clip to hold a plurality of cartridges, said clip and cartridges introduceable as a unit into the said magazine opening, the clip

comprising a pair of interlocked members, means actuated by the magazine cover to disengage the cartridges from said clip members on closure of the cover, and a catch 40 carried by said magazine cover to hold the same in place.

12. In a firearm of the type designated, the combination of a magazine provided with a lateral opening of substantially the 45 same longitudinal dimension as the ammunition space of the magazine, a slidably mounted cover for said opening, an ammunition feeding spring in the magazine, means carried by the sliding cover to engage 50 and compress the spring as the cover is moved to expose the said magazine opening, a clip to hold a plurality of cartridges for simultaneous introduction of said cartridges 55 as a unit into the opening in the magazine, said clip comprising a pair of cartridge-embracing plates, one provided with inclined cam slots, the other with spurs engaging said cam slots, means actuated by the magazine cover to engage and slide the said 60 plates on each other and spread them on closure of the cover, thereby to release the cartridges from the embrace of said plates, and a catch carried by said magazine cover 65 to hold the same in place.

Signed by me at Boston, Massachusetts, this ninth (9) day of February 1914.

GEORGE PLUMMER HOWE.
